United States Patent

Des. 235,907
Patented July 15, 1975

235,907

TRUNDLE TOY

Anthony Pecoraro, 1041 Pleasant St.,
Oak Park, Ill. 60302

Filed Dec. 18, 1973, Ser. No. 425,933

Term of patent 14 years

Int. Cl. D21—01

U.S. Cl. D34—15 D

FIG. 2

FIG. 1

FIG. 3

FIG. 4

FIG. 5

FIG. 1 is a side elevational view of a trundle toy showing my new design;

FIG. 2 is a top plan view thereof;

FIG. 3 is a front elevational view thereof;

FIG. 4 is a rear elevational view thereof; and

FIG. 5 is a side elevational view thereof with various members shown in raised position.

I claim:

The ornamental design for a trundle toy, substantially as shown and described.
